CLAIM

The ornamental design for a surface configuration of vehicle, toy, and/or other replicas, as shown and described.

DESCRIPTION

This application is related to the following co-pending applications, filed on even date herewith: Application Ser. No. 29/258,847, entitled "Surface Configuration of an Air Vent for a Vehicle"; Application Ser. No. 29/258,848, entitled "Surface Configuration of an Exhaust Pipe for a Vehicle"; Application Ser. No. 29/258,850, entitled "Surface Configuration of a Rear Bumper for a Vehicle"; Application Ser. No. 29/258,851, entitled "Surface Configuration of a Front Bumper for a Vehicle"; Application Ser. No. 29/258,852, entitled "Surface Configuration of Vehicle, Toy, and/or Other Replicas"; and Application Ser. No. 29/258,843, entitled "Surface Configuration of Vehicle, Toy, and/or Other Replicas".

FIG. 1 is a front, left perspective view of a surface configuration of vehicle, toy, and/or other replicas according to my novel design;

FIG. 2 is a rear, left perspective view thereof;

FIG. 3 is a right side view thereof;

FIG. 4 is a left side view thereof;

FIG. 5 is a front view thereof;

FIG. 6 is a rear view thereof; and,

FIG. 7 is a top view thereof.

The broken lines are for illustrative purposes only and form no part of the claimed design.
